UNITED STATES PATENT OFFICE

ANDRÉ HUET, OF PARIS, FRANCE, ASSIGNOR TO THE SUPERHEATER COMPANY, OF NEW YORK, N. Y.

SUPERHEATER

Application filed May 11, 1929, Serial No. 362,322, and in France May 12, 1928.

The invention relates to superheaters which comprise tubular serpentine units through which the steam circulates as it is being superheated and has for its object the provision of such superheater elements that will not become distorted in use. On account of this absence of distortion, the new units are especially well adapted for making baffles of adjacent lengths of the elements in the

10 manner hereinafter described.

The invention will be described in connection with the drawings herewith in which Fig. 1 shows a superheater element in accordance with the improvement; Fig. 2 shows 15 such an element shaped to form a baffle; Fig. 3 is a section on line 3—3 of Fig. 2; Fig. 4 is a further figure illustrating a unit when there are two baffles provided; and Fig. 5 is a section 20 on line 5—5 of Fig. 2 looking in the direction indicated by the arrows.

In Fig. 1 the steam is admitted to the header 1 and is taken off from header 2, these two headers being of any desired construction. Attached to them is a plurality of 25 superheater elements of which one is shown at 3. The gases heating the superheater are assumed to flow in the opposite direction from the steam flow as indicated by the arrows 4, although this is not essential. The 30 rate of expansion of the length or leg 5 from the point 6 to the point 7 as its temperature rises from ordinary atmospheric temperature to operating temperatures will be different from the rate of expansion of the 35 length or leg 8 and the latter in turn will be different from the rate of expansion of the length or leg 9 which in turn varies from that of length 10 and so on progressively to the lengths 11 and 12. This difference is due 40 to the differing temperatures of the metal. The temperature of the metal at any given point is only a little higher than that of the steam flowing through the element at that point. The steam temperature increases 45 gradually from the point of inlet to the point of outlet, and the expansion per unit length of the straight portions increases correspondingly from the inlet towards the outlet. Thus the metal in the leg 5 expands at a 50 somewhat smaller rate per unit length than

the metal in the leg 8. To compensate for this different rate of expansion the legs are made of unequal length, the cooler leg being made longer by an amount corresponding to the difference in temperature. As a result 55 the points 15 and 16 will remain relatively fixed although the point 7 will move away from both of them. Similarly the rate of expansion between 8 and 9 will vary but the total expansion of the legs 8 and 9 will be the 60 same so that point 14 will remain fixed relatively to 7. Similarly the point 17 will remain fixed relatively to 16, the point 18 will remain fixed relatively to 14 and 7 and so on to the end so that the point 19 is fixed relatively to 18, 14 and 7 and the point 20 is fixed 65 relatively to the points 17, 16 and 6.

As a result there is no distortion of the elements such as occurs frequently in practice when all of the straight portions 5 to 12 are 70 made equal in length. It is obvious that the amount by which the straight portions must progressively be relatively shortened will depend upon the circumstances such as the temperature of the steam at the inlet, its temperature at the outlet and the rate of heat-transfer. These are quantities which can all be determined quite closely so that the relative lengths necessary for these straight portions can be 75 quite closely calculated.

With an element of this general type in which there is no material distortion, it is quite feasible to construct baffles according to the plan next to be described in connection with Figs. 2, 3 and 5. The lengths of 80 the straight portions 5, 8, 9, etc. are again shown as progressively diminishing in accordance with the above description. At a point near the middle of this superheater is shown a baffle made by bending into a common plane the two straight portions 21 and 22 of the first element, 24 and 25 of the next element, and so on. Instead of connecting their right-hand ends by means of a loop such as those connecting the ends of the straight portions elsewhere, return bends as shown at 85 23 are used. These return bends are of such shape that the two legs 21 and 22, 24 and 25, etc., are closely adjacent to each other. The 90 spacing of the several superheater elements 95 100

is such that the adjacent legs of neighboring units are substantially in contact with each other. In this manner a baffle is constructed. The absence of any distortion in the several lengths will keep the baffle tight. If an attempt were made to build such a baffle with a set of elements in which the several straight portions were all of the same length it would be impossible to keep the baffle tight on account of the warping of the units.

Referring to Fig. 4 there are here shown two baffles 26 and 27 formed similarly to the one described in connection with Figs. 2 and 3. The straight portions of the elements diminish progressively here as in the former case thus insuring the absence of warping and a permanent tightness of the baffle.

I have described my invention in the above as applied to apparatus in which the fluid flowing through the tubular elements is heated on its course. It will be obvious that the invention is not restricted in this regard but is likewise applicable to a case where the fluid is cooled, and the temperature of the fluid and therefore of the tubes progressively diminishes from inlet to outlet. The straight lengths in any case vary in length to compensate for the different rates of expansion.

I claim:

- 30 1. In apparatus of the class described, the combination of two fixed headers and a plurality of tubular elements through which a fluid to be heated flows, each element comprising a plurality of parallel straight portions progressively diminishing in length in the direction of the flow and return portions connecting them into zig-zag form, the straight portions of each element being in a vertical plane except certain of them which lie between straight portions of neighboring elements thereby forming a baffle.
- 45 2. In apparatus of the class described, a tubular element of zig-zag form through which a fluid flows whose temperature changes progressively from inlet to outlet, the lengths of the several straight portions of the element being progressively different by amounts substantially to equalize the total expansions of the several straight portions.
- 55 3. In apparatus of the class described, a tubular element through which a fluid to be heated flows, the element being of zig-zag formation and the several straight portions being of progressively decreasing length in the direction of the fluid flow, the decrease being such as substantially to equalize the total expansions of the several straight portions.
- 60 4. In apparatus of the class described, the combination of two fixed headers and a plurality of tubular elements through which a fluid to be heated flows, each element being zig-zag in form with an even number of straight portions, the straight portions progressively diminishing in length in the direc-

tion of the flow, the elements being in spaced parallel relation with spaces substantially equal to the tube diameter, some of the straight portions of each element being bent into a common plane to form a baffle.
